UNITED STATES PATENT OFFICE

115,386

DESIGN FOR A COMBINATION MOTION PICTURE PROJECTOR AND PEDESTAL THEREFOR

Karl Brenkert, Detroit, Mich.

Application May 8, 1939, Serial No. 84,865

Term of patent 14 years

To all whom it may concern:

Be it known that I, Karl Brenkert, a citizen of the United States, residing at Detroit, in the county of Wayne and State of Michigan, have invented a new, original, and ornamental Design for a Combination Motion Picture Projector and Pedestal Therefor, of which the following is a specification, reference being had to the accompanying drawing, forming part thereof.

Figure 1 is a side elevation of a combination motion picture projector and pedestal therefor, showing my new design, and

Figure 2 is a front elevation thereof.

I claim:

The ornamental design for a combination motion picture projector and pedestal therefor, as shown herein.

KARL BRENKERT.
